(57) **CLAIM**

The ornamental design for container with lid, as shown and described.

DESCRIPTION

FIG. 1 is a top perspective view of a container with lid; FIG. 2 is a front elevational view of the container with lid as seen in FIG. 1, with the rear elevational view being identical; FIG. 3 is a right elevational view of the container with lid as seen in FIG. 1, with the left elevational view being identical; FIG. 4 is a top planar view of the container with lid as seen in FIG. 1;

FIG. 5 is a top perspective view of a second embodiment of a container with lid;

FIG. 6 is a front elevational view of the container with lid as seen in FIG. 5, with the rear elevational view being identical; FIG. 7 is a right elevational view of the container with lid as seen in FIG. 5, with the left elevational view being identical; FIG. 8 is a top planar view of the container with lid as seen in FIG. 5;

FIG. 9 is a top perspective view of a third embodiment of a container with lid;

FIG. 10 is a front elevational view of the container with lid as seen in FIG. 9, with the rear elevational view being identical; FIG. 11 is a right elevational view of the container with lid as seen in FIG. 9, with the left elevational view being identical; FIG. 12 is a top planar view of the container with lid as seen in FIG. 9; FIG. 13 is a top perspective view of a fourth embodiment of a container with lid; FIG. 14 is a front elevational view of the container with lid as seen in FIG. 13, with the rear elevational view being identical; FIG. 15 is a right elevational view of the container with lid as seen in FIG. 13, with the left elevational view being identical; FIG. 16 is a top planar view of the container with lid as seen in FIG. 13; FIG. 17 is a top perspective view of a fifth embodiment of a container with lid; FIG. 18 is a front elevational view of the container with lid as seen in FIG. 17, with the rear elevational view being identical; FIG. 19 is a right elevational view of the container with lid as seen in FIG. 17, with the left elevational view being identical; FIG. 20 is a top planar view of the design for the container with lid as seen in FIG. 17; FIG. 21 is a top perspective view of a sixth embodiment of a container with lid; FIG. 22 is a front elevational view of the container with lid as seen in FIG. 21, with the rear elevational view being identical; FIG. 23 is a right elevational view of the container with lid as seen in FIG. 21, with the left elevational view being identical;

FIG. 24 is a top planar view of the container with lid as seen in FIG. 21; FIG. 25 is a top perspective view of a seventh embodiment of a container with lid; FIG. 26 is a front elevational view of the container with lid as seen in FIG. 25, with the rear elevational view being identical; FIG. 27 is a right elevational view of the container with lid as seen in FIG. 25, with the left elevational view being identical; FIG. 28 is a top planar view of the container with lid as seen in FIG. 25; FIG. 29 is a top perspective view of an eighth embodiment of a container with lid; FIG. 30 is a front elevational view of the container with lid as seen in FIG. 29, with the rear elevational view being identical; FIG. 31 is a right elevational view of the container with lid as seen in FIG. 29, with the left elevational view being identical; FIG. 32 is a top planar view of the container with lid as seen in FIG. 29; FIG. 33 is a top perspective view of a ninth embodiment of a container with lid; FIG. 34 is a front elevational view of the container with lid as seen in FIG. 33, with the rear elevational view being identical; FIG. 35 is a right elevational view of the container with lid as seen in FIG. 33, with the left elevational view being identical; and, FIG. 36 is a top planar view of the container with lid as seen in FIG. 33.
